CONTAINER FOR MICROSCOPIC GLASS BEADS
USED FOR CLEANING AND DEBURRING

Richard R. Compton, Rte. 2, Washington, Mo. 63090

Filed Apr. 29, 1968, Ser. No. 11,648

Term of patent 14 years

Int. Cl. D15—06

U.S. Cl. D49—1

FIG. 1

FIG. 2

FIGURE 1 is a perspective view showing my new design for a container for microscopic glass beads used for cleaning and deburring; and

FIGURE 2 is a rear elevational view of FIGURE 1 with the broken line structure being shown for illustrative purposes only.

I claim:

The ornamental design for a container for microscopic glass beads used for cleaning and deburring, as shown and described.

UNITED STATES PATENT OFFICE
CERTIFICATE OF CORRECTION

Design No. 213,638

March 25, 1969

Richard R. Compton

It is certified that error appears in the above identified patent and that said Letters Patent are hereby corrected as shown below:

In the grant, line 3, after "Missouri," insert -- assignor to Zero Manufacturing Company, of Washington, Missouri, a corporation of Missouri, --; line 13, "Richard R. Compton, his heirs" should read -- Zero Manufacturing Company, its successors --. In the heading to the drawing and printed specification, line 3, "Richard R. Compton, Rts. 2, Washington, Mo. 63090" should read -- Richard R. Compton, Washington, Mo., assignor to Zero Manufacturing Company, Washington, Mo., a corporation of Missouri --.

Signed and sealed this 21st day of April 1970.

(SEAL)
